UNITED STATES PATENT OFFICE.

BENJAMIN DAVIES, OF WEST HOBOKEN, NEW JERSEY, ASSIGNOR TO
L. STRAUS & SONS, OF NEW YORK, N. Y.

DESIGN FOR A BOWL OR VESSEL.

SPECIFICATION forming part of Design No. 31,738, dated October 31, 1899.

Application filed September 29, 1899. Serial No. 732,117. Term of patent 7 years.

To all whom it may concern:

Be it known that I, BENJAMIN DAVIES, a subject of the Queen of Great Britain, residing at West Hoboken, in the county of Hudson and State of New Jersey, have invented and produced a new and original Design for Bowls or Vessels; and I do hereby declare the following to be a full, clear, and exact description of the same, reference being had to the accompanying drawings, forming a part thereof.

This invention relates to an original design for bowls or vessels, and it is embodied in the configuration and arrangement of features presently to be described, and shown in the accompanying drawings.

In the drawings, Figure 1 is a side elevation of a bowl, showing the design. Fig. 2 is a side elevation with the bowl turned to a position ninety degrees from that shown in Fig. 1. Fig. 3 is a bottom plan view.

The design, as illustrated, comprises a circular central bottom field A. From diametrically opposite points near the upper edge 25 of the bowl valleys b extend in gracefully curved diverging lines, terminating at the edge of said field A, forming the two large generally heart-shaped fields B, as seen in Fig. 2. Within the fields between the valleys 30 b are other valleys b', substantially parallel thereto. From the opposite side of the field A valleys c diverge toward and terminate at the valleys b', thereby forming the opposite substantially diamond-shaped fields C.

35 c' are valleys substantially parallel with valleys c and also terminating at the valleys b'. From the valleys b, at opposite sides, extend valleys d, converging toward the upper edge of the vessel and forming, with valleys

d', substantially parallel with the valleys b, 40 generally diamond-shaped fields D at the opposite sides of the vessel and intermediate the heart-shaped fields.

In the central field A is illustrated a star, and in fields D are also stars. In the fields 45 between the valleys c c' and b b' are represented series of separated star-shaped figures, and between the valleys b d' are shown decorations.

At the sides of the vessel, between the fields 50 D and B, are small diamond-shaped decorated fields E.

F indicates small fields below the fields D, and these also are fancifully decorated.

G indicates substantially lanceolate fields 55 between the valleys b' c'.

The edges of the vessel or receptacle above the fields D, B, and E are curved and indented to form rounded projections or scallops.

60 The essential features of the design consists in the dish or vessel having the opposite large fields B, the opposite intermediate fields D, the central field A, and the fields formed between the several substantially parallel 65 valleys.

Having thus described my invention, what I claim as new, and desire to secure by Letters Patent, is—

The design for a bowl or vessel, substantially as shown and described.

In testimony whereof I affix my signature in presence of two witnesses.

BENJAMIN DAVIES.

Witnesses:

JULIA V. FARRELL,
GEORGE WIESE.
